UNITED STATES PATENT OFFICE.

JAMES REA WELTON, OF SCRANTON, PENNSYLVANIA.

THREAD CLEANER FOR TEXTILE MACHINES.

Application filed February 7, 1924. Serial No. 691,145.

To all whom it may concern:

Be it known that I, JAMES REA WELTON, a resident of Scranton, county of Lackawanna, State of Pennsylvania, have invented 5 certain new and useful Improvements in a Thread Cleaner for Textile Machines, set forth in the annexed specification, reference being had therein to the accompanying drawing.

10 This invention comprises a thread cleaner for textile machines.

It is contemplated among the objects of the invention, to provide a device of this character which may be readily attached to 15 and detached from a portion of a textile machine, which will take up a very small space and have few parts, so arranged as to be practically fool proof.

It is another object to provide a cleaner 20 having a fixed blade and a movable blade associated therewith, the mechanism for moving the movable blade being simplified and standardized so that it can be readily manufactured and assembled and locked in 25 adjusted position.

Still a further object is to provide means 30 for carrying a guide, associated with the cleaner, the arrangement being such that it may be readily attached and detached, and provision is also made for porcelain or 35 friction reducing portions where the thread might come in contact with the device.

Other objects and advantages will in part 40 be apparent and in part be brought out more fully in the description which follows:

An embodiment of the invention is illustrated in the accompanying drawings, the following views being shown:

Figure 1, is a view in front elevation of 45 a cleaner embodying my invention;

Fig. 2, is a bottom view of the same;

Fig. 3, is a view in vertical section on line 3—3 of Fig. 1;

Fig. 4, is a fragmentary view in rear elevation of the back portion of the device shown in Fig. 1;

Fig. 5, is a fragmentary detail view, partly in section illustrating a means for mounting the blade moving instrumentality.

50 In these views, 1 designates a body or support provided with means for attaching it to a textile machine or the like, here shown as screw receiving openings 2.

Upon the body there are carried two sets 55 of spaced-apart blade supporting arms 3, 3, and 4, 4. These may be formed as a part of

the support 1, and extend therefrom in spaced-apart relation. Between the arms 3—3, there is disposed a fixed blade 5, suitably secured to the arms as by rivets or the like 6. This blade has a curved lower portion 7, and it rests, upon its upper surface, on a portion of the support 1 disposed between and connecting the sets of arms, this portion acting as a support for the fixed 65 blade and a bearing upon which a movable blade can slide.

Between the arms 4, 4, there is disposed a movable blade 8. This has a curved lower portion 9, and an edge extending downwardly to cooperate with a corresponding edge of the blade 5, and act as a cleaner. An edge of the movable blade bears upon a portion of the support 1, and means are provided for moving the blade with relation to 75 the fixed blade 5.

As here shown there is a cut out portion or slot 10, in the inside of each arm 4, extending from the open end of the arms, downwardly therebetween. Into this slot 80 there is adapted to fit a flanged portion 11 of an adjusting screw 12. The screw has a threaded portion extending into a threaded opening on the movable blade, and a knurled thumb nut 13, carried on a portion extending 85 outwardly between the arms. A keeper 14 fits between the arms filling the space above the adjusting screw and maintaining it in place. The keeper may be suitably secured as by a rivet 15.

90 Means are provided for locking the movable blade in adjusted position, and as here shown there is provided a set screw 16, threaded into an opening in one of the arms 4 and adapted to engage a surface of the 95 movable blade. This set screw is hollowed out for the reception of a wrench and is so placed as not to project beyond the surface of the arm when set.

Means are also provided for carrying a 100 threaded guide, and as here shown an opening is formed in the lower portion of arms 4, into which a wire or the like 17 is adapted to pass. This is secured adjustably therein as by a set screw 18 best seen in Figs. 1 and 105 4. The wire is extended upwardly and thence into alignment with the opening between the blades where it is provided with the usual porcelain or like guide 19, here shown in the form of the well known "pig-tail".

110 The portion of the arms which might come

in contact with the thread are preferably surfaced with a friction minimizing agent such as porcelain or the like, indicated by numeral 20 in Fig. 2. As another precaution against wear and cutting of the thread, a bar 21 is disposed in openings carried by oppositely disposed arms and extends between the blades at a point above the bottom of the slot formed by the blades. This bar 10 is preferably formed of hardened steel or the like and rounded to minimize friction. It is maintained in position by a plug of shellac or the like cementitious material indicated at 22. To remove the bar, it is merely 15 necessary to melt the shellac when it may be slipped from the openings.

From the foregoing it will be apparent that the present invention provides a simple, practical device of few parts, easily assembled and which meets the objects and advantages enumerated. While it has been disclosed in connection with the present embodiment, it will be understood that I do not wish to be limited to the precise form of 25 this disclosure, as many changes in the general construction and arrangement of the parts are contemplated as within the scope of the invention as set forth in the claims.

What I claim is:

30 1. A thread cleaner for textile machines comprising a support; members, in spaced-apart relation associated with said support; a blade disposed between certain of the members; certain of the members being provided 35 with a slot therein; a blade disposed between the members in proximity to the slot; an adjusting screw connected with the blade; a collar on the adjusting screw, disposed in

the slot between the members; and an operating nut on the screw 40

2. A thread cleaner for textile machines comprising a support; members, in spaced-apart relation associated with said support; a blade disposed between certain of the members; certain of the members being provided 45 with a slot therein; a blade disposed between the members in proximity to the slot; an adjusting screw connected with the blade; a collar on the adjusting screw, disposed in the slot between the members; an operating 50 nut on the screw, and a thread guiding member formed from hardened material and having a friction reducing surface, disposed in proximity to the opening between the blades. 55

3. A thread cleaner for textile machines comprising a support; members, in spaced-apart relation associated with said support; a blade disposed between certain of the members; certain of the members being provided 60 with a slot therein; a blade disposed between the members in proximity to the slot; an adjusting screw connected with the blade; a collar on the adjusting screw, disposed in the slot between the members; an operating 65 nut on the screw, a thread guiding member formed from hardened material and having a friction reducing surface, disposed in proximity to the opening between the blade, and means for securing the thread guiding member in place comprising a plastic cementitious material disposed in an opening in the support in proximity to the guide member. 70

In testimony whereof I affix my signature.

JAMES REA WELTON.
